UNITED STATES PATENT OFFICE.

JOHN J. MEYER, OF NEW YORK, N. Y.

DESIGN FOR A SANDWICH-SIGN.

No. 37,740.

Specification for Design.

Patented Dec. 19, 1905.

Application filed October 27, 1905. Serial No. 284,757. Term of patent 7 years.

To all whom it may concern:

Be it known that I, JOHN J. MEYER, a citizen of the United States, and a resident of the city of New York, borough of Manhattan, in the county and State of New York, have invented a new, original, and ornamental Design for a Sandwich-Sign, reference being had to the accompanying drawings, in which—

Figure 1 is a front elevation of a sign, showing my new design. Fig. 2 is a rear elevation of the same, and Fig. 3 is a side elevation.

I claim—

The ornamental design for a sandwich-sign as shown.

JOHN J. MEYER.
